TEMPERATURE CONTROL APPARATUS

John A. McLean, Jr., Springfield, Mass., assignor
to Westinghouse Electric Corporation, East
Pittsburgh, Pa., a corporation of Pennsylvania

Application April 22, 1947, Serial No. 743,049

6 Claims. (Cl. 62—4)

1

This invention relates to controls for refrigerators embodying a secondary volatile refrigerant system and, more especially, to a location for the thermo-sensitive bulb of such a control.

It is an object of the invention to provide a control system for the primary refrigerating apparatus in a refrigerator employing a secondary volatile refrigerant circuit, which system maintains satisfactory temperatures for freezing foods.

It is another object of the invention to provide a control system for a refrigerator of the type described, which system maintains substantially uniform temperatures in spite of variations in ambient temperatures.

It is a further object of the invention to provide a control system for a refrigerator of the type described, in which the thermostat may have a large temperature differential.

These and other objects are effected by the invention as will be apparent from the following description and claims taken in connection with the accompanying drawings, forming a part of this application, in which:

Fig. 1 is a view in elevation of a refrigerator with parts broken away and embodying the invention;

Fig. 2 is a sectional view on the line II—II of Fig. 1; and

Fig. 3 is a view in perspective of the secondary refrigerant circuit and a phantom view of the inner liner of the refrigerator cabinet to which the secondary circuit is secured.

Referring now to the drawings for a description of the invention, the reference numeral 10 designates the outer metal shell of a refrigerator cabinet 12. A horizontal partition 14 divides the cabinet 12 into an upper compartment 16 for the freezing and storing of frozen foods and a lower compartment 18 for the refrigerant-supplying apparatus 20. The upper compartment 16 comprises an inner metal liner 22 spaced from the outer metal shell 10 and the partition 14. Thermal insulating material is disposed between the side, rear, and top walls of the inner liner 22 and the corresponding walls of the outer shell 10. Thermal insulating material 24 is also disposed between the bottom wall of the inner liner 22 and the partition 14. A door 25 of similar construction closes the front opening of the cabinet 12.

A primary evaporative cooling unit 26 is secured, by means not shown, in the upper portion of the upper compartment 16. The cooling unit 26 may be of any convenient design but is here shown as comprising a broad U-shaped element

2

27 formed of two metal sheets 28 and 30 which are welded together. The sheets 28 and 30 are embossed to provide refrigerant passages 32, a refrigerant inlet 34 to said passages 32, and refrigerant headers 36. The cooling unit 26 also comprises a metal top plate 38 and a metal rear plate 40 secured to the top edges and the rear edges, respectively, of the U-shaped element 27.

A convoluted metal refrigerant tube 42 is brazed to the upper surface of the top plate 38 and the rear surface of the rear plate 40 and communicates at its lower end with the inlet 34 of the U-shaped element 27. The cooling unit here described is more fully shown and described in the patent application, Serial No. 668,950 of Jules N. Saler, filed May 10, 1946.

The cooling unit 26 is adapted for freezing foods and is supplied with a volatile refrigerant liquid by the refrigerant apparatus 20 in the lower compartment 18. The apparatus 20 comprises a sealed casing 44 enclosing a compressor and an electric motor for driving the compressor. A suction tube 46 connects the casing 44 with one of the headers 36. The compressor withdraws refrigerant vapor from the header 36 through the suction tube 46, compresses the vapor, and forces it through a tube 48 into a condenser 50 wherein the refrigerant vapor is liquefied. The refrigerant liquid flows through a capillary tube 52 to the tube 42 wherein a portion of the refrigerant liquid vaporizes. The remaining refrigerant liquid and the refrigerant vapor passes to the inlet 34 of the U-shaped element 27 wherein the complete vaporization of the refrigerant liquid takes place.

The lower portion of the upper compartment 16 is maintained at a temperature of about 0° F. and constitutes the area where frozen foods may be stored. This portion is cooled by a conventional flow of air from the cooling unit 26 and also by a secondary volatile refrigerating circuit 54. The secondary circuit 54 consists of a closed tube which has been evacuated and filled partially with a volatile refrigerant liquid through the filler pipe 55. The secondary circuit 54 includes a first portion 56 lying adjacent to and in heat-transfer relation with some of the convolutions of the tube 42 on the rear plate 40 of the cooling unit 26. The first portion 56 serves to condense refrigerant vapor into a liquid. The secondary circuit 54 also comprises a second portion 58 secured to the side, rear and bottom walls of the inner liner 22. The second portion 58 cools the upper compartment 16 and absorbs the heat which penetrates

through the thermal insulation 24 thereof. The secondary circuit also includes a third portion 60 which conducts the vaporized refrigerant from the second portion 58 to the first portion 56 of the secondary circuit 54. The secondary circuit 54 also comprises a fourth portion 62 for conducting the refrigerant liquefied in the first portion 56 to the second portion 58. A part 64 of the fourth portion 62 lies in the thermal insulation 24 of the refrigerator cabinet 12 and out of thermal contact with other portions of the refrigerator so that the temperature of part 64 correspond substantially to the temperature of the refrigerant flowing therethrough. A tube 66 is intimately brazed to the part 64 for a purpose which will be explained subsequently.

The electric motor in the sealed casing 44 of the refrigerant-supplying apparatus 20 is energized through the electrical leads 68 and a thermostatic control 70 is interposed in one of the leads 68. The control 70 comprises a switch 72 actuated by a metal bellows 74 through an over-center spring 76 which affords a snap-acting movement to the switch 72 in a manner well understood in the art. The metal bellows 74 communicates through a tube 78 with a bulb 80 located in the tube 66.

The bellows 74, the tube 78, and the bulb 80 are evacuated and charged with a small quantity of a volatile liquid so that the pressure within the bellows 74 is responsive to the temperature of the liquid in the bulb 80 when the refrigerant apparatus 20 is in operation. It will thus be apparent that the switch 72 is opened and closed in response to the temperature of the bulb 80 and that the switch 72 controls the operation of the electric motor and hence of the compressor to actuate the compressor whenever the temperature of the bulb 80 rises above a predetermined temperature such as 1° F. and stops the compressor whenever the temperature of the bulb 80 is reduced to a second predetermined temperature such as minus 7° F. Since the temperature of the bulb 80 corresponds to the temperature of the part 64 of the secondary circuit, the refrigerating apparatus 20 is controlled by the temperature of the refrigerant flowing therethrough.

The advantages of placing the thermostatic bulb 80 in heat transfer relationship with the refrigerant liquid flowing through the part 64 are as follows:

First, when a large quantity of food is placed in the primary evaporative cooling unit 26 to be frozen, the refrigerating apparatus 20 will run substantially continuously. This is caused by the fact that the refrigerant liquid in the primary cooling unit 26 is vaporized rapidly by the relatively warm food. This tends to raise the suction pressure of the refrigerant supplying apparatus 20 since its pumping capacity is limited. The increased suction pressure causes the temperature of the refrigerant in the tube 42 to rise, and the part 64 of the secondary circuit is not cooled to the assumed temperature of minus 7° F. at which the thermostatic control 70 stops the compressor. The refrigerating apparatus 20 is thus caused to operate at its maximum capacity to freeze the food.

Second, the thermostatic control 70 may be of the wide temperature differential type, the temperature differential between starting and stopping the apparatus 20 being about 8° F. This is caused by the fact that the changes in the temperature of the part 64 are closely related

to the changes in the temperature of the primary cooling unit 26 because the refrigerant liquid condensed in the first portion 56 by the primary cooling unit 26 flows directly through part 64.

5 The changes in temperature of the primary cooling unit 26, in turn, are directly responsive to the running cycles of the refrigerant apparatus 20, so that the temperature of part 64 normally drops when the refrigerating apparatus 20 is in operation and rises when said apparatus stops.

Third, the location of the bulb 80 on the secondary refrigerant circuit insures a constant temperature in the frozen food storage area of the upper compartment 16 when the ambient temperature of the refrigerator varies. It will be readily apparent that if the temperature of the refrigerant liquid supplied to the second portion 58 of the secondary circuit 54 is held between the aforementioned predetermined limits, the temperature 15 of this portion 58 will also be held substantially to these limits in spite of changes in the heat load caused by increases in the ambient temperature. This alone would not keep the temperature in the storage area substantially constant 20 because the increased heat leakage through the walls of the cabinet not cooled by the portion 58 of the secondary circuit 54 (such as the door 25, the upper wall, and the upper portions of the side and rear walls of the compartment 16) would 25 allow additional heat to leak in. This additional heat leakage, however, is offset by the lower temperature at which the primary cooling unit 26 is forced to operate to absorb all of the heat supplied by the first portion 56 of the secondary circuit 54. This lower temperature of the primary cooling unit 20 thus additionally cools the storage compartment by convection and tends to hold its temperature constant.

Fourth, the temperature of the frozen food 30 storage area tends to remain constant if relatively warm foods are placed therein, since the primary cooling unit 26 will be forced to operate at a lower temperature under these conditions to absorb all the heat supplied by the secondary circuit 54 as explained above.

It will be apparent from the above that this invention provides a location for the control bulb of a refrigerator utilizing a secondary refrigerant circuit, which location affords rapid freezing of foods in the primary cooling unit, a substantially constant temperature in the food storage area, and allows the use of a wide differential control.

While I have shown my invention in but one form, it will be obvious to those skilled in the art that it is not so limited, but is susceptible of various changes and modifications without departing from the spirit thereof.

What I claim is:

- 60 In refrigerating mechanism, the combination of a primary evaporator, apparatus for supplying said primary evaporator with a volatile liquid refrigerant and for withdrawing vaporized refrigerant from said evaporator, thermostatic control for rendering said apparatus active and inactive, and a secondary volatile refrigerant circuit operating at the same pressure throughout, said secondary circuit having a first portion in heat transfer relationship with said primary evaporator for condensing refrigerant vapor in said secondary circuit, said circuit having a second portion for absorbing heat to vaporize refrigerant liquid in said circuit, said secondary circuit having a third portion for conducting refrigerant vapor from said second portion to said
- 65
- 70
- 75

first portion, said circuit also having a fourth portion for conducting refrigerant liquid from said first portion to said second portion, said thermostatic control including a temperature-responsive actuating element in heat-transfer relationship substantially solely with said fourth portion of said circuit.

2. In a refrigerator, the combination of a thermally insulated chamber, a primary evaporator for cooling said chamber, refrigerating apparatus for supplying said primary evaporator with refrigerant liquid and for withdrawing refrigerant vapor from said evaporator, a secondary volatile refrigerant circuit operating at a uniform pressure throughout, said circuit having a first portion in heat transfer relationship with said primary evaporator, a second portion for cooling said chamber, a third portion for conducting refrigerant vapor from said second portion to said first portion, and a fourth portion for conducting refrigerant liquid from said first portion to said second portion, said fourth portion having at least a part which does not lie in direct heat-conducting relationship with said primary evaporator, or with said first, second, or third portion of the secondary circuit, and a thermostatic control for rendering said apparatus active and inactive, said thermostatic control including a temperature-responsive actuating element lying in heat-transfer relation with said part of the fourth portion of said circuit.

3. The refrigerator structure defined in the immediately preceding claim wherein the primary evaporator is located within said chamber.

4. In a refrigerator, the combination of a chamber having metal walls and thermal insulating material on the outer surface of said walls, a primary evaporator in the upper portion of said chamber, refrigerating apparatus for supplying said primary evaporator with refrigerant liquid and for withdrawing refrigerant vapor from said evaporator, a secondary volatile refrigerant cir-

cuit operating at a uniform pressure throughout, said circuit having a first portion in heat-transfer relationship with said primary evaporator, a second portion in heat-transfer relationship with extensive portions of said metal walls, a third portion for conducting refrigerant vapor from said second portion to said first portion, and a fourth portion for conducting refrigerant liquid from said first portion to said second portion, said fourth portion having at least a part which does not lie in direct heat-conducting relationship with any of said metal walls, with said primary evaporator or with said first, second, or third portion of the secondary circuit, and a thermostatic control for rendering said apparatus active and inactive, said control including a temperature-responsive actuating element lying in heat-transfer relationship with said part of the fourth portion of said circuit.

10 5. The refrigerator structure defined in the immediately preceding claim wherein said second portion is not in heat-transfer relationship with all of the walls of said chamber and wherein the primary evaporator assists in cooling the

15 25 6. The refrigerator structure defined in the immediately preceding claim wherein said part of the fourth portion of said circuit and said temperature-responsive element are embedded in said thermal insulating material.
